UNITED STATES PATENT OFFICE.

ANDREW H. SMITH, OF NEW YORK, N. Y.

STEAM-TURBINE ENGINE.

No. 824,955.

Specification of Letters Patent.

Patented July 3, 1906.

Application filed February 5, 1906. Serial No. 299,399.

To all whom it may concern:

Be it known that I, ANDREW H. SMITH, a citizen of the United States, and a resident of the borough of Manhattan, in the city and State of New York, have invented a new and useful Improvement in Steam-Turbine Engines, of which the following is a specification.

The object of my invention is to provide certain improvements in steam-turbine engines whereby the efficiency of the engine is increased by increasing the force of impact of the steam by the introduction of a suitable powder into the steam just before it is brought into engagement with the piston vanes or wings.

A practical embodiment of my invention is represented in the accompanying drawing, which represents so much of a steam-turbine engine as will give a clear understanding of my invention, the parts being shown partially in side elevation and partially in section.

The cylinder of the engine is denoted by 1, the piston by 2, and the piston vanes or wings by 3. The expanding steam-nozzle is denoted by 4, through which steam is forced upon the vanes or wings from any suitable source of supply.

30 The powder-nozzle 5 is located within the steam-nozzle 4, to which powder-nozzle a feed-pipe 6 leads from a powder-reservoir 7 of the desired shape and size. A powder-supply pipe 8 is provided for the reservoir 7, and a supply-pipe 9 for the admission of the heating and pressure medium is also provided for the said reservoir 7. The pipes 6, 8, and 9 are provided with cocks 10, 11, and 12, respectively.

40 In operation as the steam is passed through the expanding nozzle 4 into engagement with the vanes or wings 3 of the piston 2 the powder—which is preferably powdered graphite, for instance—is introduced into the jet of steam through the nozzle 5 under the desired pressure just before the impact of the jet of steam upon the vanes or wings of the piston. The weight of the jet will thus be increased and in this way will add to the momentum 45 and at the same time make the jet effective for a greater distance from the point of impact than has heretofore been possible with a jet of steam alone. This powdered graphite may be heated to the proper temperature 50 and placed under the required pressure by any suitable means—such, for instance, as

introducing superheated steam into the reservoir 7 through the pipe 9 from any suitable source. (Not shown herein.) After the powdered graphite has been used in connection with the turbine it may again be used by introducing the same into the reservoir 7 through the pipe 8. It will be seen that the graphite will readily separate from the steam and may be used over and over again, as practically none of the powder is lost in the operation of driving the turbine. This powder may be employed dry or mixed with water or other fluid to any desired consistency and may be introduced into the expanding nozzle 4 under any desired pressure.

By loading the jet of steam with the graphite or other powder a relatively slow moving medium is provided having a greater and more persistent momentum than the steam alone, and thus causing a heavier though slower impact on the piston vanes or wings. It will also be seen that the graphite will receive and retain a high degree of heat, which will prevent the rapid condensation of the steam.

What I claim is—

1. In a steam-turbine engine, a steam-nozzle and means for introducing a powder into the steam as it is passing through the said nozzle.

2. In a steam-turbine engine, a steam-nozzle and means for introducing powdered graphite into the steam as it is passing through the said nozzle.

3. In a steam-turbine engine, a steam-nozzle and means for introducing a powder at a high temperature into the steam as it is passing through the said nozzle.

4. In a steam-turbine engine, a steam-nozzle and means for introducing powdered graphite at a high temperature into the steam as it is passing through the said nozzle.

5. In a steam-turbine engine, a steam-nozzle and means for introducing a powder under pressure into the steam as it is passing through the said nozzle.

6. In a steam-turbine engine, a steam-nozzle and means for introducing powdered graphite under pressure into the steam as it is passing through the said nozzle.

7. In a steam-turbine engine, a steam-nozzle and means for introducing a powder at a high temperature and under pressure into the steam as it is passing through the said nozzle.

8. In a steam-turbine engine, a steam-nozzle and means for introducing powdered graphite at a high temperature and under pressure into the steam as it is passing through the said nozzle. 25
9. In a steam-turbine engine, an expanding steam-nozzle and means for introducing a powder into the steam as it is expanding in said nozzle. 30
10. In a steam-turbine engine, an expanding steam-nozzle and means for introducing powdered graphite into the steam as it is expanding in said nozzle. 35
11. In a steam-turbine engine, an expanding steam-nozzle and means for introducing a powder at a high temperature into the steam as it is expanding in said nozzle. 40
12. In a steam-turbine engine, an expanding steam-nozzle and means for introducing powdered graphite at a high temperature into the steam as it is expanding in said nozzle. 45
13. In a steam-turbine engine, an expanding steam-nozzle and means for introducing

a powder under pressure into the steam as it is expanding in said nozzle.

14. In a steam-turbine engine, an expanding steam-nozzle and means for introducing powdered graphite under pressure into the steam as it is expanding in said nozzle. 50

15. In a steam-turbine engine, an expanding steam-nozzle and means for introducing powder at a high temperature and under pressure into the steam as it is expanding in said nozzle. 55

16. In a steam-turbine engine, an expanding steam-nozzle and means for introducing powdered graphite at a high temperature and under pressure into the steam as it is expanding in the said nozzle. 60

In testimony that I claim the foregoing as my invention I have signed my name, in presence of two witnesses, this 2d day of February, 1906.

ANDREW H. SMITH
